AEROSOL INTER-DENTAL PROPHYLACTIC MOUTHWASH DISPENSER

Garrison Trupp, 4600 York Road, and Bernard Trupp,
3900 N. Charles, both of Baltimore, Md.

Filed Oct. 30, 1964, Ser. No. 32,395

Term of patent 14 years

(Cl. D24—1)

FIG. 1

FIG. 2

FIG. 3

FIG. 4

FIG. 5

FIG. 6

FIG. 7

FIG. 1 is a side elevation of an aerosol inter-dental prophylactic mouthwash dispenser, showing our new design wherein the dispensing tip curves downwardly.

FIG. 2 is a rear elevation thereof.

FIG. 3 is a front elevation thereof.

FIG. 4 is a top plan thereof.

FIG. 5 is a bottom plan thereof.

FIG. 6 is a side elevation of an aerosol inter-dental prophylactic mouthwash dispenser, showing a modified form of our new design wherein the dispensing tip is straight; and

FIG. 7 is a side elevation of an aerosol inter-dental prophylactic mouthwash dispenser, showing another modified form of our new design wherein the dispensing tip is angled upwardly and downwardly as shown.

The portions shown in broken lines are for illustrative purposes only.

We claim:

The ornamental design for an aerosol inter-dental prophylactic mouthwash dispenser, as shown and described.
